(57) **CLAIM**

The ornamental design for a lighted dental camera, as shown and described.

DESCRIPTION

FIG. 1 is a perspective view of a lighted dental camera showing our new design;

FIG. 2 is a front elevational view thereof;

FIG. 3 is a right side elevational view thereof, the left side elevational view being a mirror image thereof;

FIG. 4 is a rear elevational view thereof;

FIG. 5 is an enlarged top plan view thereof;

FIG. 6 is an enlarged bottom plan view thereof;

FIG. 7 is an enlarged view of the encircled portion in FIG. 1; and,

FIG. 8 is an enlarged view of the encircled portion in FIG. 2. The broken lines encircling enlargement portions of the design form no part of the claimed design.

1 Claim, 4 Drawing Sheets
